UNITED STATES PATENT OFFICE.

PAUL FREDERICK VOLAND, OF CHICAGO, ILLINOIS, ASSIGNOR TO THE KEMPER-THOMAS COMPANY, OF CINCINNATI, OHIO, A CORPORATION OF NEW JERSEY.

DESIGN FOR A VIZOR OR EYE-SHADE MASK.

No. 37,551.

Specification for Design.

Patented Sept. 12, 1905.

Application filed June 12, 1905. Serial No. 264,959. Term of patent 7 years.

To all whom it may concern:

Be it known that I, PAUL FREDERICK VOLAND, a citizen of the United States, residing at Chicago, in the county of Cook and State of Illinois, have invented a new, original, and ornamental Design for a Vizor or Eye-Shade Mask, of which the following is a specification.

The figure is a plan view of a vizor or eye-shade mask, showing my new design.

I claim—

The ornamental design for a vizor or eye-shade mask, as shown.

PAUL FREDERICK VOLAND.
